UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAYBOLT STRUCTURE.

1,392,236.

Specification of Letters Patent. Patented Sept. 27, 1921.

Application filed September 12, 1919. Serial No. 323,364.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Staybolt Structures; and we do hereby declare the following to be a full, clear, and exact description 10 of the invention, such as will enable others skilled in the art to which it appertains to make and use the same.

This invention relates to improvements in staybolt structures for boilers,—one object 15 of the invention being to provide a universally movable or adjustable mounting for connecting the head of a staybolt with a boiler sheet whereby alinement of the staybolt with its points of connection with the 20 respective boiler sheets shall be insured, and to provide in such a mounting, a simple bearing ring for the bolt head, which shall be adjustable to compensate for variations in the lengths of bolts and which may also 25 be employed to test the bolt.

With this and other objects in view, the invention consists in certain novel features of construction and combinations of parts as hereinafter set forth and pointed out in 30 the claims.

In the accompanying drawings; Figure 1 is a sectional view showing an embodiment of our invention, and Fig. 2 is a plan view of the adjustable bearing ring.

35 1 represents a boiler sheet having an opening 2, a portion of the wall of which may be rounded or curved transversely of the sheet to provide a rounded or curved seat 3 on which a bearing sleeve or member 4 40 may have a universally movable or adjustable mounting. In the embodiment of our invention shown in the drawing, the bearing sleeve 4 passes through the opening in the boiler sheet and has a rounded exterior 45 portion to rest against the curved or rounded seat 3 in the boiler sheet. By mounting the sleeve in such manner that it shall be universally movable, said sleeve can be so adjusted as to insure accurate alinement of the staybolt with its points of connection with the respective boiler sheets and when the bearing sleeve shall have been thus adjusted, it will be united to the boiler sheet by means of a weld 5.

55 The bearing sleeve 4 is provided in prox-

imity to its lower or inner end with an internal annular shoulder 6 and the inner wall of said sleeve is threaded as indicated at 7, and said threaded portion may extend from the shoulder 6 to the upper or 60 outer end of the sleeve.

A bearing ring 8 is threaded into the sleeve 4 and, under normal conditions, may rest on the internal annular shoulder 6. This ring is made, interiorly, with a rounded 65 seat 9 for the rounded head of a staybolt 10. The opening at the inner end of the sleeve 4 may be made flaring as may also the inner end of the bearing ring, to facilitate the "swing" of the staybolt. The inner 70 end of the bolt may be secured to the inner boiler sheet 11 in any suitable manner.

The threaded bearing ring 8 is provided with notches 12 to receive a suitable wrench, and it will be seen that by turning said 75 bearing ring, compensation for variations in the lengths of bolts may be effected. Furthermore, the bearing ring may be employed for testing purposes. That is to say; if, by applying turning force to the ring, 80 said ring turns freely for an abnormal distance, this will indicate that the bolt is broken.

A closure 13 for the sleeve is threaded into the outer end of the latter and may be 85 provided with a flange 14 to overlie the outer end of the sleeve,—said closure also having an angular part 15 to receive a wrench.

Having fully described our invention what 90 we claim as new and desire to secure by Letters-Patent, is:—

1. In a staybolt structure, the combination with a boiler sheet having an opening, of a bearing sleeve having a threaded interior portion and an internal shoulder near its lower end, a bearing ring located in said bearing sleeve over said internal shoulder and threaded to mesh with the threads in the sleeve, said ring having a seat for the 95 head of a staybolt, a staybolt, having a head seated on said bearing ring, and means closing the outer end of said sleeve.

2. In a staybolt structure, the combination with a boiler sheet having an opening, 100 of a bearing sleeve having an initial universally movable mounting in the boiler sheet, a weld uniting said sleeve to the boiler sheet, said sleeve threaded interiorly and having an internal shoulder below said 110

threaded portion, a bearing ring threaded into said sleeve above said shoulder and having a rounded seat for the head of a staybolt, a staybolt having a rounded head 5 mounted on the rounded seat afforded by said ring, and a closure threaded into the outer end of said sleeve.

In testimony whereof, we have signed this specification in the presence of a subscribing witness.

BENJAMIN E. D. STAFFORD.
ETHAN I. DODDS.

Witness:

EDWIN S. RYCE.
